UNITED STATES PATENT OFFICE

2,050,814

CRATE

Edward C. Steiger, Chicago, Ill., assignor to Chicago Mill and Lumber Company, Chicago, Ill., a corporation of Delaware

Application March 2, 1936, Serial No. 66,544

9 Claims. (Cl. 217—5)

This invention relates to nesting or stacking crates or boxes of the tapered type having downwardly converging side walls to permit nesting of the crates and furthermore having improved 5 reinforced metal end walls provided with inwardly projecting corrugations forming side grooves on the interior of the crate for the reception of the ends of the side walls; said end walls furthermore being provided with integral top, bottom 10 and side flanges and with outwardly expanded bars or ribs adapted to serve as protuberances to facilitate nesting of the crates one within another when empty with the bars of an upper 15 crate seating upon the upper edges of the end rail members of a lower crate for holding the reinforcing rims or frames of the crates separated to permit easy separation of the crates.

It is an object of this invention to provide a 20 stacking crate or box having side and bottom walls constructed of wood or fiber and provided with metal end walls flanged for mounting purposes and corrugated for the double purpose of reinforcing the end walls and providing pockets or grooves on the inner sides of the end walls 25 for the reception of the ends of the side walls of the crates to prevent said side walls from being forced inwardly.

It is also an object of this invention to provide 30 an improved type of stacking crate having the end walls thereof constructed of corrugated metal and having upper portions thereof expanded outwardly to form stacking bars or ribs below the top rail members to facilitate nesting of the crates and separation of the same as desired.

35 It is a further object of this invention to provide a stacking crate having an end wall constructed of sheet metal formed to provide inwardly projecting ribs or corrugations to form side wall receiving pockets on the inner sides of the end walls.

40 It is furthermore an object of this invention to provide a stacking crate or box provided with a unitary sheet metal end wall to form side wall receiving pockets on the inner side of the end 45 wall, said end wall furthermore having a horizontal portion thereof expanded outwardly to form a nesting bar to hold the frames or rims of nested crates properly spaced apart to facilitate removal of one crate from within another.

50 It is an important object of this invention to provide improved stacking or nesting crates of the tapered type provided with a top frame and having sheet metal end walls corrugated for strength and for the purpose of providing guide 55 pockets on the inner sides of the end walls for the

reception of the ends of the side walls of the 5 crate, said metal end walls furthermore each being provided with an integral nesting bar and with an outwardly projecting top flange adapted to project into a groove on the inner side of the top frame end member.

Other and further important objects of this 10 invention will be apparent from the disclosures in the specification and the accompanying drawings.

The invention (in a preferred form) is illustrated in the drawings and hereinafter more 15 fully described.

On the drawings:

Figure 1 is a fragmentary vertical detailed 15 section taken through the end portions of two nested crates or boxes with the upper box being illustrated in elevation to show the position of the nesting bar resting on the top frame end rail of the lower crate for holding the top frames of 20 the two crates spaced apart to facilitate removal of one crate from the other.

Figure 2 is a fragmentary horizontal detailed 25 section of the crate taken on line II—II of Fig. 1.

Figure 3 is a fragmentary vertical detailed section taken on line III—III of Fig. 1.

Figure 4 is a horizontal detailed section taken on line IV—IV of Fig. 1, illustrating the cross section of the metal end wall and also illustrating portions of the bottom and side walls of the 30 crate.

Figure 5 is an isometric view of one of the metal 35 end wall units removed from the crate and illustrating the outwardly expanded stacking bar, the various flanges of the end wall, and the reinforcing corrugations the two outermost ones of which provide receiving pockets on the inner side of the end wall for the reception of the ends of the side walls of the crate.

As shown on the drawings:

The improved nesting crate or box comprises 40 a wood or fiber bottom 1 provided with ventilation eyelets or openings 2 and reinforced by means of longitudinally disposed bottom rails or runners 3 and transverse cleats or brace bars 4. Each end 45 of each of the bottom runners 3 is rounded at 5 and is provided with an end slot 6 intermediate the top and the bottom of the runner and extending inwardly a short distance as clearly illustrated in Fig. 1.

The body of the crate or box is of the tapered 50 form and comprises two side walls 7 constructed of wood, fiber board, or other suitable material. The side walls 7 are shaped and mounted to form upwardly and outwardly inclined walls. Secured 55

to the lower outer longitudinal margin of each of the side walls 7 is a metal angle strip 8 having a short bottom flange which extends beneath the bottom edge of the side walls 7, as clearly illustrated in Fig. 3. Each of the bottom runners 3 is provided with an outer groove 9 (Fig. 3) for the reception of the lower reinforced edge of one of the side walls 7. The lower margins of the side walls 7 are secured by nails or other suitable means to the bottom runners 3 and to the side edges of the bottom or floor 1.

The two ends of the body of the crate or box are closed by improved end wall units. Each of the end wall units as clearly illustrated in Fig. 5, 15 is stamped or formed out of sheet metal and comprises a metal end wall 10 having inwardly projecting corrugations or ribs 11 formed thereon to reinforce the wall and form a comparatively strong end of thin sheet metal. As clearly illustrated in Fig. 4 the two longer outermost corrugations or ribs are designated 14 and serve as guides or stop means against which the ends of the side walls 7 are adapted to abut and be held in place with the assistance of side flanges 12 20 which are integrally formed by bending over the side margins of the end wall 10. The bottom margin of the end wall 10 is bent inwardly to form a bottom flange 13. As clearly illustrated in Fig. 5 the lower ends of the side flanges 12 are bent 25 inwardly against the bottom surface of the end portions of the bottom flange 13 and are spot welded in place. The outermost corrugations or ribs designated by the reference numeral 14 together with the side flanges 12 of the end wall 30 form sockets or pockets at 15 for receiving the end margins of the side walls 7 of the crate to strengthen the corners of the crate. The side flanges 12 of the end walls are provided with apertures 16 to receive nails or screws for fastening the end margins of the side walls to the flanges 12 of the end walls 10. The bottom flange 13 of each of the end walls 10 together with the bent over lower ends of the side flanges 12 project into the end slots 6 of the bottom runners or rails 3 35 thereby permitting the major portion of the bottom flange 13 to seat against the bottom of one of the transverse reinforcing bars or cleats 4 to which the bottom flange is secured by screws, nails or other suitable means. The top margin of 40 the end wall 10 is deflected outwardly to provide a top flange 17.

For the purpose of nesting the improved crates or boxes each of the end walls 10 is provided at the upper portion thereof below the top flange 55 17 with a nesting bar or rib 18 which is formed by bulging or expanding a horizontal portion of the end wall 10 outwardly across the wall above the upper ends of the corrugations 11. The arrangement provides two spacing bars or protuberances across the metal end walls of the crate body 60 a short distance below the end rails of the top frame of the crate.

Secured around the upper margin of the body of the crate is a top frame comprising side rails 65 or bars 19 and end rails or bars 20. The side rails 19 have the inner sides thereof grooved to seat over the upper margins of the side walls 7 while the end rails 20 are each provided with a slot 21 on the inner side thereof extending from end to 70 end for receiving the outwardly directed top flange 17 of the end wall as clearly illustrated in Fig. 1. Metal corner brackets 22 are securely fastened in position to cover the intersecting or abutting ends of the side and end rails 19 and 20 thereby reinforcing 75 the corners of the top frame of the crate.

As clearly illustrated in Fig. 1 the stacking bars 18 are positioned across the end walls 10 of the crate directly below the top reinforcing frame end rails to provide a convenient arrangement whereby a crate may be nested within a similar crate with the nesting bars 18 of an upper crate resting upon the tops of the end rails 20 of a lower crate so that the upper reinforcing frames of the crates are held in spaced relation so that the crates may be easily lifted out of one another by gripping 10 an upper crate beneath the frame members.

The improved metal end wall units of the crate provide an arrangement for enclosing the ends of the side walls and the bottom to form a rigid crate construction the strength of which is increased 15 by the corrugated end walls which being constructed of metal produce a crate of great strength without materially increasing the weight or the cost of the crate. The guide ribs 14 serve the double purpose of being reinforcing means as well 20 as stop members and guides for the ends of the side walls of the crate, while the bars 18 act to strengthen the upper portions of the end walls of the crate as well as provide suitable spacing or nesting means for facilitating the separation 25 of nested crates.

If it is desired to provide a crate of the type herein described with stacking irons such as are disclosed in the patent to W. O. Brown No. 1,982,367, dated November 27, 1934, the stacking 30 bars 18 may be omitted since the stacking irons when used may serve as the separating means between the top frames of the crates when it is desired to nest the crates one within another.

It will, of course, be understood that various details of construction may be varied through a wide range without departing from the principles of this invention, and it is, therefore, not the purpose to limit the patent granted hereon otherwise than is necessitated by the scope of the appended claims.

I claim as my invention:

1. A nesting crate or box having an open top, inclined sloping side walls, a bottom of less area than the top, corrugated metal end walls enclosing the ends of the side walls and the bottom, outwardly projecting flanges integrally formed on the metal end walls, and a top frame engaged around the crate and having slots on the interior thereof for receiving the outwardly projecting flanges of the end walls.

2. A nesting container having an open top, side walls, a bottom connecting the side walls, corrugated metal end walls enclosing the ends of the side walls and the bottom and secured thereto, and nesting bars expanded outwardly transversely of the upper portions of the metal end walls to hold nested containers in spaced relation to facilitate separation of the nested containers.

3. A nesting container comprising a bottom, side walls and unitary metal end walls having inwardly projecting ribs integrally formed thereon to hold the side walls in place, said end walls also having outwardly expanded nesting bars formed on the end walls between said ribs.

4. A stacking container comprising a bottom, side walls secured thereto, corrugated metal end walls engaged over the ends of the side walls and the bottom and secured thereto, a top frame engaged around the upper rim of the container, said metal end walls having inwardly projecting stop ribs formed thereon to engage against the inner sides of the end margins of the side walls to assist in holding the side walls in place, and nesting bars integrally formed on the end walls.

between the stop ribs and above the corrugations to hold the container nested in spaced relation within a similar container.

5. A tapered nesting container including a bottom and side walls, and end walls connected to the bottom and to said side walls with each of said end walls comprising a corrugated metal plate having bottom and side flanges integrally formed thereon, a top flange integrally formed on the upper margin of the metal end wall, stop means integrally formed near the side margins of the end wall and projecting inwardly adjacent the ends of the container side walls, and nesting members expanded outwardly from the end wall 10 between the edges thereof and below the top flange of the end wall.

6. A nesting crate comprising walls, a bottom, and a reinforcing rim secured to said walls, a pair of said opposite walls having inwardly projecting ribs formed thereon and also having outwardly projecting elongated nesting bars formed thereon, said pair of opposite walls also having flanges integrally formed thereon and projecting into the material forming the reinforcing rim of the crate.

25 7. A nesting crate including in combination end wall units each comprising a reinforced metal plate, bottom and side flanges integrally formed

on the plate and projecting away from one side of the plate, a top flange integrally formed on the plate and projecting away from the opposite side of the plate, stop ribs integrally formed on the plate parallel to and closely adjacent the side flanges of the plate, and a nesting bar on the plate beneath and parallel to the top flange. 5

8. A nesting crate including in combination, a wall unit comprising a reinforced metal plate having side and bottom flanges integrally formed 10 thereon and a top flange projecting from the plate in a direction opposite from the bottom flange, and nesting means expanded from the metal forming the metal plate and terminating short of the side edges of the plate. 15

9. A nesting crate including in combination a wall unit comprising a corrugated metal plate, having a top flange and side and bottom flanges integrally formed thereon with the top flange projecting in a direction opposite from that of 20 the bottom flange, stop ribs integrally formed on one side of the plate parallel to and spaced from the side flanges of the plate, and nesting means expanded from the material forming the plate and positioned beneath the top flange of the 25 plate and between said stop ribs.

EDWARD C. STEIGER.
